CRANK CASE AND OIL PUMP HEATER

Filed March 28, 1930

Fig. 3.

By Clarence O'Brien
Attorney

UNITED STATES PATENT OFFICE

EDWARD L. SOBOLIK, OF DAVID CITY, NEBRASKA

CRANK CASE AND OIL PUMP HEATER

Application filed March 28, 1930. Serial No. 439,711.

This invention relates to a heater for heating crank cases and the oil pump arranged within the crank case.

The primary object of this invention is to provide an electrical heating unit adapted to be arranged within the bottom of the crank case at the lower end of the oil pump within the crank case to prevent freezing of the oil within the crank case and further to provide a heating unit of this character which may be so operatively connected with the screen of the oil pump as to prevent accumulation of ice on the oil pump screen in order to maintain at all times perfect lubrication especially while the motor is cold.

Other objects and advantages of the invention will become apparent during a study of the following description taken in connection with the accompanying drawings:

Figure 1 is a fragmentary detail sectional view taken through a crank case showing in elevation the oil pump arranged therein for clearly illustrating the application of my invention thereto,

Figure 2 is a bottom plan view of the oil pump showing the application of my invention thereto,

Figure 3 is a diagrammatic view illustrative of the wiring system.

With reference more in detail to the drawings, it will be seen that the reference character 5 designates the block of an internal combustion engine and the reference character 6 the crank case of the engine. The oil pump which depends from the cylinder block 5 into the crank case may be of conventional construction and is designated generally by the reference character P.

The oil pump screen on the lower end of the pump and in parallelism to the bottom of the crank case 6 is designated by the reference character 7 and in this instance, it is seen that the screen is substantially circular.

The invention per se consists of a tubular casing 8 formed of copper, brass, or, and preferably, aluminum. In forming the tubing 8 it will be noted that the tubing is suitably formed intermediate its ends to pro-

vide a somewhat circular part in the nature of a split ring, the ends of which terminate in branches 9 bent at right angles to extend upwardly as at 10, the upper end of the vertically disposed part or extension 10 terminating in laterally disposed ends extending outwardly of the block 5 through suitable sleeves 11 threaded within the block 5 as clearly shown to advantage in Figure 1.

Arranged within the circular part of the tubular casing is a suitable heating wire 12 which is preferably in the nature of nichrome wire, and the circular part 8 of the casing is placed against the bottom face of the circular screen 7 and supported thereon through the bottom of a cross rod 13 extending transversely of the screen and screwed or otherwise secured to the screen adjacent the edge of the screen as at 14.

Through one of the branches 10 is passed a suitable wire 16 which at its inner end is suitably connected to one end of the heating wire 12 and at its opposite end terminates in a contact forming part of a suitable switch S, which switch S may be arranged within convenient reach of the operator.

The wire 16 passing through the switch S to the ammeter designated by the reference character A in Figure 3 arranged in the circuit leading from the source of electrical energy, preferably a battery, designated by the reference character B. A second wire 17 is connected at one end to the other end of the heating wire 12 and this wire extends through the other of the extensions 10 to a suitable ground 18.

Preferably, in securing the ends of the heating wire 12 to the said ends of the wires 16 and 17 the said ends are preferably twisted together instead of soldering. Of course, the wires are suitably insulated from the tubing by encasing all of the bare wires in a suitable asbestos stocking as clearly suggested in Figure 1.

From the foregoing then it will be seen that the circuit to my improved heating unit may be readily and manually controlled through the medium of the switch S which may be placed on the dashboard, steering gear or any other part of the vehicle within

convenient reach of the operator and that a heater of this character will maintain a desired temperature within the crank case and especially about the screen of the oil pump within the crank case thus preventing freezing of the lubricant within the crank case and on the screen 7 so that perfect lubrication of the internal combustion engine may be had at all times even during cold and inclement weather and which will further prevent freezing of the oil pump.

It is thought that from the foregoing description taken in connection with the accompanying drawings a clear understanding 15 of the operation, utility and advantages of an invention of this character will be had by those skilled in this art without a more detailed description.

Even though I have herein shown and 20 described the preferred embodiment of my invention, it is to be understood that the same is susceptible to changes fully comprehended by the spirit of the invention as herein described and the scope of the appended claims.

Having thus described my invention, what I claim as new is:

1. In an electrical heater of the class described, a tubular casing having a circular 30 part adapted for disposition in the crank case of an internal combustion engine between the bottom of the crank case and the screen of the oil pump within the crank case, angularly disposed branches extending 35 from the ends of the circular part upwardly through the cylinder block of the internal combustion engine, an electrical heating wire arranged within the circular part of said tubular casing, said heating wire being ar- 40 ranged in an electrical circuit, the wires of which extend through said branches, said circuit wires and said electrical heating wire being suitably insulated from the branches and casing respectively, and a switch ar- 45 ranged in said circuit for controlling the heating unit.

2. In an electrical heater of the class described, a tubular casing having a circular 50 part adapted for disposition in the crank case of an internal combustion engine between the bottom of the crank case and the screen of the oil pump within the crank case, angularly disposed branches extending from the ends of the circular part upwardly 55 through the cylinder block of the internal combustion engine, an electrical heating wire arranged within the circular part of said tubular casing, said heating wire being ar- 60 ranged in an electrical circuit, the wires of which extend through said branches, said circuit wires and said electrical heating wire being suitably insulated from the branches and casing respectively, and a member ex- 65 tends transversely of said screen and the circular part of said casing, said member

being secured at its ends to said screen for retaining said circular part of the casing on said screen.

In testimony whereof I affix my signature.
